UNITED STATES PATENT OFFICE.

GIOVANNI NORBERTI, OF BOSTON, MASSACHUSETTS.

COLLAPSIBLE AND CONVERTIBLE CHAIR.

1,240,243.

Specification of Letters Patent. Patented Sept. 18, 1917.

Application filed February 24, 1916. Serial No. 80,143.

To all whom it may concern:

Be it known that I, GIOVANNI NORBERTI, a subject of the King of Italy, residing at Boston, in the county of Suffolk and Commonwealth of Massachusetts, have invented new and useful Improvements in Collapsible and Convertible Chairs, of which the following is a specification.

The object of the present invention is to provide a collapsible chair that is capable of being converted into a cot, stretcher, or table. The invention as shown by the drawings is embodied in a structure that is designed especially for military hospital use, its compactness when collapsed facilitating storage and transportation, and its several uses making it particularly well adapted to fulfil the requirements of military field operations.

Referring to the drawings that form a part of this specification:—

Figure 1 represents a side elevation of a collapsible folding structure embodying the present invention and adjusted to form an arm chair. An adjustable leg-rest and a foot-rest arranged to support the latter, are indicated by broken lines.

Fig. 2 represents a longitudinal vertical section of the structure shown by Fig. 1 adjusted to provide a cot or table as the case may be.

Fig. 3 represents an end elevation of the side structure in the condition represented by Fig. 2, the direction of view being from right to left with reference to Fig. 2.

Fig. 4 represents a side elevation of the structure at the left hand of Fig. 2, the element hereinbefore referred to as a "leg-rest" being arranged in position to serve as a head-rest, and a movable extension bar being shown in extended position to afford means whereby the structure may be carried when used as a stretcher.

Fig. 5 represents a top plan view of the complete structure collapsed into a substantially flat form for storage or transportation.

The same reference characters indicate the same parts wherever they occur.

Referring to Fig. 5 the structure includes two open rectangular frames one of which is arranged inside the other in nested relation. The outer or larger one of said frames comprises parallel side bars 10, 10, a cross-bar 11 connecting bars 10, 10 near one end and a cross-bar 12 connecting bars 10, 10 near the other end. The inner or smaller

one of said frames comprises longitudinal bars 13, 13, a cross-bar 14 connecting the latter near one end, and a cross-bar 15 connecting bars 13 near the other end. These two frames are connected, one with the other, by pivot members or trunnions 16, 16, the latter being arranged to extend through bars 10 and 13 on a common axis. Members 16 extend also through links 17, 17 of arm-rests 18 hereinafter described. Cross-bar 15 is in this instance a relatively small rod and is surrounded by a sleeve 19. A rectangular sheet 20 of suitable thin sheet material such as canvas is anchored at one end to cross-bar 11 (Figs. 1 and 2) and at the other end it extends around sleeve 19, being provided with a loop or pocket 21 therefor. The effective length of the sheet material 20 is such that said element is drawn tight by the two said frames when the latter are nested substantially in a common plane as shown by Figs. 2 and 5, the sheet material in such case being adapted to serve as a table top, or as a bed bottom, as the case may be. On the other hand when the two said frames are adjusted to any one of their several chair-forming angular relations (see Fig. 1) the sheet material 20 is slackened and serves as a chair-bottom and back-rest.

The two said rectangular frames are capable of being adjusted to a plurality of angular relations to afford reclining positions of different degrees, and for this purpose said larger or outer frame is provided with struts 22 and the bars 13 of the smaller frame are provided with notches 23 arranged in series. Struts 22 are connected to bars 10 by pivot members 24 and are connected one to the other by a transverse rod 25. Notches 23 are adapted to receive rod 25 as shown by Fig. 1, and as the rod is moved toward the lower ends of bars 13 the reclining quality of the chair is increased.

A leaf 26 is connected to cross-bar 12 and is arranged to serve as a foot-rest when the structure is adjusted to form a chair. This foot-rest is capable of swinging relatively to the bars 10, 10, being connected to the latter by pivot members 27, 27. Struts 28 are carried by the foot-rest and are connected to the latter by pivot members 29, 29. The struts are connected by cross-bar 30 so that they are to all intents and purposes a unit. When it is desired to use the element 26 as a foot-rest the struts 28 are placed in the position shown by solid lines in Fig. 1, but

when said element is not being used as a foot-rest the struts are capable of being folded into nested relation therewith as shown by Figs. 2 and 5.

- 5 A leaf 31 is mounted upon rod 15 and is capable of swinging about the latter. This leaf is adapted to serve as a leg-rest or as a head-rest, according to whether the entire structure is in chair-form, or in bed-form.
- 10 As shown by broken lines in Fig. 1 the element 31 is in position to serve as a leg-rest, and the element 26 as represented by broken lines is arranged to engage and support the lower end of the leg-rest. For this purpose the leg-rest is provided with a plurality of notches 32 into which the free end of the foot-rest may be inserted. By shifting member 26 from one notch 32 to another the angular position of the leg-rest may be changed.
- 15 In this connection it is to be noted that the chair is adjusted to its most upright position, and that if it were adjusted to a position of relatively great reclination the rod 15 would be considerably lower than it is according to Fig. 1. This would have the effect of placing the leg-rest in a position more nearly horizontal than that shown.

The arm-rests 18 are connected to the links 17 by pivot members 33. Links 34 connect the arm-rests with struts 22. The members 22 and 34 are connected by pivot members 35. Screw bolts 36 connect links 34 with the arm-rests, and thumb-nuts 37 having screw-threaded connection with bolts 36 are arranged to bear against the sides of the arm-rests to clamp the latter against the links 34. By so clamping the arm-rests relatively to the links the former may be held stationary, but when the clamping stress is relieved the arm-rests may be moved to various positions.

When it is desired to convert the structure into a table, or into a cot without a head-rest, the leg-rest may be moved into nested position as shown in Figs. 2 and 5.

Continuing the transformation of the structure from a chair to a table or cot, the thumb-nuts 37 are loosened to afford freedom of movement of the arm-rests. Struts 22 are detached from bars 13 thus permitting the two said rectangular frames to be moved relatively to each other about their pivots or trunnions 16, to the nested relation shown by Figs. 2 and 5. Sheet material 20 is thus tightened forming a suitable top for a table or a suitable bottom for a bed. Referring to Fig. 2 the bars 13 are retained in the position shown, by a pair of locking plates 44. These plates are mounted upon cross-bar 11 by means of pivot members 45. Preparatory to moving the frames to nested relation plates 44 would be moved to make a clear passage way for the ends of bars 13 and would then be moved under said ends as shown by Fig. 2.

The element 26 is usable to support one end of the larger frame when the structure is adjusted in the form of a table or bed, and at the same time movable legs 50 are usable to support the other end. When the element 26 is used for the purpose last stated it may be locked in the desired angular relation, as shown by Figs. 2 and 3, by braces 51. These braces are connected to bars 13 by pivot members 52, and they are provided with eyes adapted to fit over the projecting ends of pivot pins 29. In order to guard against accidental dislodgment of the brace rods 51 from the pins 29, the element 26 is provided with retaining devices 53 each of which is in the form of a leaf spring. The devices 53 are affixed to the element 26 and cover the outer ends of pins 29 but they may be sprung outwardly from the ends of said pins. Eyes 55 formed in the members 53 are adapted to receive the ends of said pins, and when the free ends of members 53 are swung away from the pins the members 51 may be attached to or detached from the pins. When the brace rods 51 are not used as such they may be arranged to extend substantially parallel to the bars 13, and to overlie the retaining pins 56 that project from the confronting faces of said bars for that purpose.

The legs 50 that are usable to support the other end of the structure are connected to a cross-bar 57 by pivot members 58. The ends of bar 57 are affixed to bars 10, 10. The legs 50 are represented in supporting position by solid lines in Fig. 3, and are represented in folded position by broken lines in the same figure. A movable retaining device 59 connected to cross-bar 57 by a pivot pin 60 is adapted to hold the legs in folded position. The free ends of the legs have reduced portions 61 that are adapted to enter eyes 62 formed in plates 63 affixed to the free ends of struts 22, and when the legs and struts are connected in the relation shown by Figs. 2 and 3 the load upon the legs is sustained by plates 63. The reduced ends of the legs do not touch the floor, ground or other supporting surface, the greater area of the ends of struts 22 being utilized for that purpose.

If it should be desired to provide the cot with a head-rest the elements 31 may be used for that purpose. In such case element 31 would be arranged to project over bar 12 as shown by Fig. 4, and would be sustained by said bar.

If it should be desired to use the cot for the purpose of a stretcher the end portion 10' of bars 10 would serve as one pair of carrying handles while the sliding extension members 64 could be extended as shown by Fig. 4 to provide another pair of carrying handles. The members 64 are arranged to slide endwise in rigid guides 65 that are affixed to the bars 10. Studs or spurs 66 carried by and projecting from the members 64

are arranged to coact with two of the guides 65 to prevent the members 64 from being withdrawn from the guides.

I claim:

- 5 1. A collapsible structure comprising two rectangular frames arranged one within the other, coöperative trunnions connecting said frames, said frames being capable of relative angular movement about said trunnions, 35
- 10 a rectangular sheet of thin flexible material fastened at one edge to one of said frames and at the opposite edge to the other one of said frames in lines parallel to the axis of said trunnions, said frames being ar- 40
- 15 ranged to sustain said sheet material in a slack condition and in a taut condition according to their angular relation, bracing means arranged to brace said frames in chair-forming relation with said sheet ma- 45
- 20 terial in a slack condition to form the seat and back, a foot-rest pivotally connected to one end of the outer said frame, two coöperative legs pivotally connected to the other end of said outer frame, said legs and said 50
- 25 bracing means having separable portions ar- ranged to coact to brace said legs in frame- supporting position, and means arranged to brace said foot-rest in frame-supporting po- 55
- 30 sition.
- 30 2. A collapsible structure comprising an open rectangular frame, a smaller open rectangular frame arranged within the first

said frame, trunnions connecting said frames so that they may be nested in a common plane and moved relatively to various angular relations, a rectangular 'sheet' of thin flexible material fastened along one edge to one of said frames and along the opposite edge to the other one of said frames, whereby it is held taut to form a bed-bottom when said frames are nested, and whereby it is sustained in a slack condition to form a chair-seat and chair-back when said frames are in an angular relation, means arranged to hold said frames in chair-forming angular relation, a leg-rest pivotally mounted on said smaller frame, supporting means pivotally connected to the first said frame and ar- ranged to sustain said leg-rest in operative position when said frames are in chair-forming relation, said supporting means being arrangeable to support one end of the first said frame when said frames are in said nested relation, said leg-rest being arranged to be sustained by said frames, conjointly, to provide a head-rest when said frames are in said nested relation, and means arranged to support the other end of the first said frame when said frames are in said nested relation.
